(57) **CLAIM**

The ornamental design for an X-ray generator tube for a medical imaging device, as shown and described.

DESCRIPTION

FIG. 1 is a front view of a design for an X-ray generator tube for a medical imaging device.

FIG. 2 is a rear view of the X-ray generator tube for a medical imaging device.

FIG. 3 is a bottom view of the X-ray generator tube for a medical imaging device.

FIG. 4 is a top view of the X-ray generator tube for a medical imaging device.

FIG. 5 is a right side view of the X-ray generator tube for a medical imaging device.

FIG. 6 is a left side view of the X-ray generator tube for a medical imaging device.

FIG. 7 is a left top and rear perspective view of the X-ray generator tube for a medical imaging device.

FIG. 8 is a left top and front perspective view of the X-ray generator tube for a medical imaging device.

FIG. 9 is a right and rear perspective view of the X-ray generator tube for a medical imaging device; and,

FIG. 10 is a rear perspective view of the X-ray generator tube for a medical imaging device.

The broken lines in FIGS. 1-10 are included for the purpose of illustrating environmental structure and form no part of the claimed design.
